DESIGN FOR A FRUIT AND VEGETABLE CONDITIONER CABINET

Frank R. West, Detroit, Mich.

Application March 2, 1938, Serial No. 75,536

Term of patent 14 years

To all whom it may concern:

Be it known that I, Frank R. West, a citizen of the United States of America and residing at Detroit, in the county of Wayne and State of Michigan, have invented a new, original, and ornamental Design for a Fruit and Vegetable Conditioner Cabinet, of which the following is a specification, reference being made to the accompanying drawing, forming part thereof. This is a continuation in part of my prior application Serial No. D-72,734, filed November 9, 1937.

Fig. 1 is a perspective view of a fruit and vegetable conditioner cabinet showing my new design with the door in opened position;

Fig. 2 is a perspective view of the cabinet shown in Fig. 1 with the door closed.

The basket arrangement forms an integral part of the cabinet.

I claim:

The ornamental design for a fruit and vegetable conditioner cabinet, substantially as shown and described.

FRANK R. WEST.
